UNITED STATES PATENT OFFICE.

LOUIS G. MAYER, OF CINCINNATI, OHIO.

CARRIAGE-SPRING.

SPECIFICATION forming part of Letters Patent No. 732,575, dated June 30, 1903.

Application filed October 4, 1902. Serial No. 125,871. (No model.)

To all whom it may concern:

Be it known that I, LOUIS G. MAYER, a citizen of the United States, residing at Cincinnati, in the county of Hamilton and State of Ohio, have invented certain new and useful Improvements in Carriage-Springs, of which the following is a specification.

My invention relates to that class of springs known as "elliptic" or "leaf" springs.

One of the objects of my invention is to secure the ends of the spring by a clamp applied to the extreme end of the spring-leaf, which clamp rotates on a center to compensate for the endwise movement of the spring as it is elongated by compression.

Another object of my invention is to strengthen the construction of the spring by doing away with the bolt-eyes in the spring, also in so arranging the clamping members so that the holding force is applied to the extreme end of the spring.

The features of my invention are more fully set forth in the description of the accompanying drawings, forming a part of this specification, in which—

Figure 1 is a side elevation of the elliptic spring embodying my improvement. Fig. 2 is a central vertical section with the clamping-bolt shown in elevation. Fig. 3 is a section on line $x-x$, Fig. 2. Fig. 4 is a section through said line $x-x$, Fig. 2, with the clamping-bolt and spring removed. Fig. 5 is a perspective view of one of the clamps. Fig. 6 is a modification of Fig. 4.

In the most complete form of construction my spring is composed of two equal members, as shown in Fig. 1; but it is adapted to be used with a single spring member.

A represents the main leaf of the upper spring member.

B represents the inner leaf of the lower member of the spring.

C represents the clamping-bolt.

D represents a segmental clamp for securing the upper spring member to its center.

E represents a segmental clamp for securing the outer end of the lower spring member in position. The forms of these two clamps are practically the same and are constructed pri-

marily as shown in Fig. 5. Each clamp is

provided with bolt-openings *a* in the disks or heads *b*. In the preferred form the heads *b'* of one clamping member are inside of the head *b* of the opposite clamping member. The bolt forms the center on which both of these clamping members independently oscillate. In order to hold these springs in fixed relative position one to the other, they are each provided with a recess *c*, which seats on opposite sides of the center bolt. In the preferred form of construction the inner periphery of the clamps are concave and fit and engage the segmental end of the spring-leaves. Preferably these leaves are slightly eccentric upon their inner sides, so as to leave a slight space between their bases and the concave base of the spring. By this means the bite of the clamping member is at the extreme end of the spring and insures a more free movement of the spring around the center than if the clamp embraced the spring over the entire concave end. It will be observed that the ends of the spring are left a slight distance asunder, so that each one may be moved without being obstructed by the other.

It will be observed that the clamping members perform the same office, one for the upper and the other for the lower leaf, and that each one oscillates on its center with its respective spring member, and they each oscillate or rotate in opposite directions. As each clamp moves with its respective spring, it avoids friction and secures ease of motion.

The spring members A B are provided with a lip *d* to insure positive engagement with its clamping member.

In the modification shown in Fig. 6 I have shown the upper clamping member provided with an overhanging lip *e*, so as to prevent the entrance of dust and dirt and also to give a better finished appearance to the spring.

By the construction herein shown and described several very important advantages are obtained. First, each spring (when composed of two members) is free to move upon a common center entirely independent of the other member; second, the clamping force is applied, preferably, to the outer end of the spring, so that the entire length is free to re-

spond to the strains; third, undue heating, welding, and swaging of the spring in order to form a bolt-eye center is avoided.

The center recesses at the end of the springs 5 are shown in the drawings as semicircular and slightly eccentric, so as to bring the clamping strain on the outer end of the spring, and is the preferred form of construction. I do not wish to limit myself to the semicircular 10 form, as an arc of a considerably less extent may be practically employed and still embody my invention. This extreme end of the spring is practically an overhanging lip, and its form may be variously modified without departing 15 from the principal feature of my invention.

Mode of operation: The spring and clamping members are secured together by the clamping-bolt, which forms the center of the 20 spring and clamps. When the springs are compressed, they will elongate and the clamping members will each independently rotate on the center bolt, the spring and clamp moving together turning on the center bolt. Each 25 spring is free, therefore, to elongate and move on its center independently of the other. The clamp-bolt serves as a center for each of the

independently-operating clamps and as a common center for the two independently-acting spring-leaves.

Having described my invention, I claim— 30

1. In an elliptic spring, the combination with a center bolt of the two independently-recessed leaves of an independent segmental clamp for each spring, each adapted to rotate on a common center bolt and move with its 35 respective spring member in opposite directions, substantially as described.

2. In combination with an elliptic spring member the ends of which are free to seat upon a common center bolt two segmental 40 clamps, each independently connected with the outside spring members, one of which is provided with a lip upon the outer side which overlaps and closes the space between each of the opposite segmental clamps, substantially 45 as described.

In testimony whereof I have hereunto set my hand.

LOUIS G. MAYER.
